United States Patent

Des. 235,637
Patented July 1, 1975

235,637

EXTERIOR MOLDED PANEL FOR DATA PROCESSING UNITS

Richard G. Clayton, Detroit, Mich., assignor to
Burroughs Corp., Detroit, Mich.

Filed Aug. 1, 1973, Ser. No. 384,488

Term of patent 14 years

Int. Cl. D25—01; D14—99

U.S. Cl. D13—1 J

FIG. 1

FIG. 2

FIG. 1 is a perspective view of an exterior molded panel for data processing units embodying my new design; and

FIG. 2 is an enlarged partial end view thereof.

The undisclosed right side is a mirror image of the side shown and the rear is plain and unornamented.

I claim:

The ornamental design for an exterior molded panel for data processing units, as shown.
